UNITED STATES PATENT OFFICE.

THOMAS A. HART, OF DANBURY, CONNECTICUT.

SLIPPING DEVICE FOR NECKTIES.

Application filed July 10, 1925. Serial No. 42,660.

To all whom it may concern:

Be it known that I, THOMAS A. HART, a citizen of the United States, and a resident of Danbury, in the county of Fairfield and 5 State of Connecticut, have invented an Improvement in Slipping Devices for Neckties, of which the following is a specification.

This invention relates to devices for facilitating the slipping of neckties through 10 turned down collars and for thus aiding in the proper adjustment and tying of the necktie without undue pulling thereon and injury thereto.

One of the objects of the invention is to 15 provide a device of the above nature capable of functioning efficiently and dependably and affording the user at all times a high degree of convenience and comfort. Another object is to provide a device of the 20 above nature which is thin and light and which does not add objectionable bulk or stiffness to the collar. Another object is to provide a device of the above nature which is simple and inexpensive. Other objects will 25 be in part obvious or in part pointed out hereinafter.

The invention accordingly consists in the 30 features of construction, combinations of elements, and arrangements of parts as will be exemplified in the structure to be herein- 35 after described and the scope of the application of which will be indicated in the following claims.

In the accompanying drawing in which is 35 shown one of the various possible embodiments of this invention,

Figure 1 is a perspective of the device as 40 it appears before being used;

Figure 2 is a perspective view showing 45 the device in use in a collar, the collar being shown in phantom;

Figure 3 is a vertical transverse section 50 through the rear of the collar, and

Figure 4 is a fragmentary view to illustrate 55 certain features of the device.

Similar reference characters refer to similar parts throughout the several views of the drawing.

As conducive to a clearer understanding 60 of the features of this invention, it may be here noted that in tying a necktie and properly adjusting the tie after the knot has been formed, it is necessary to slide the tie back and forth around the collar. In the 65 case of turned down collars, and particularly stiff collars of the turned down

type, this sliding or slipping of the necktie is not readily accomplished. The necktie wedges between the folds of the collar, and the linen walls of the collar frictionally engage the necktie so securely that oftentimes it is almost impossible to make the necktie slip. The pulling necessary to make the necktie slip is frequently ruinous to the tie and, in addition, 70 the inconvenience is a great annoyance to the wearer. To provide a device which effectively overcomes this difficulty, which is convenient to use and extremely inexpensive and which is not bulky and objectionable to 75 wear, are the dominant aims of this invention.

Referring now to the drawing, there is shown in Figure 1 a perspective of a preferred form of this invention. The device 75 shown takes the form of an elongated and straight strip 10 of thin, non-rigid and collapsible material which is capable of readily yielding to any shape and of creasing and folding to conform to the conditions under 80 which it is used. I have found that thin paper is particularly advantageous. The strip is folded along a longitudinal line preferably substantially midway between 85 its sides, and the necktie is adapted to be received between the folds thereof.

In Figure 2 the device is shown in operative position within a collar 11 and coacting with a necktie 12 therein. It is placed over the necktie with the folded edge thereof directed upwardly, and is thereby prevented from accidentally slipping downwardly from the necktie or from within the folds of the collar. The strip is preferably of a width at least twice as great as that of the necktie, so that the portion of the necktie embraced thereby is completely held out of contact with both the inner and outer folds of the collar. Also, the strip is of substantial length, for example greater than half the length of the collar from end to end, so that in operative position it covers the portion of the necktie at the back of the collar and extends well around to the sides and toward the front. 100

The side 13 of the paper strip which engages the necktie, that is, the inner surfaces of the strip when folded, is smooth and slippery so that the necktie slips readily thereover. When the material employed is paper, 110 these inner surfaces of the folded strip are preferably glazed. Thus, when the necktie

is being tied and the knot is being adjusted, the necktie slides easily over the glazed surfaces, held out of contact with the rough frictional walls of the linen collar, and may 5 be slipped around as desired with the greatest convenience. If desired, the outer surface of the folded strip may be made unglazed and rough, as shown at 14 in Figure 4, so that the paper strip will dependably 10 frictionally engage the walls of the collar and not slide around with the necktie. Except for this frictional engagement, the paper strip is free from connection with the collar, as shown in Figure 3.

15 Referring again to Figure 2, it will be seen that when the folded and originally straight strip of paper is in position over the necktie, and the tie is curved to the contour of the collar, the inner fold of the 20 strip folds and creases and readily conforms itself to the required shape. The paper is non-resilient and does not tend to spring back to its original straight contour, so as to distort or musshape the collar. The thinness and lightness of the strip and its ready 25 conformation to the required shape render its use in the collar wholly unnoticeable. It does not add objectionable bulk to the interior of the collar nor lend an added undesirable effect of stiffness.

30 In use, the paper strip may be slipped over the necktie before insertion of the necktie in the collar, and then the two may be placed together within the folds of the 35 collar. The device is extremely inexpensive and consequently a new strip may be employed each time the collar is worn or each time the user inserts a necktie in a collar for wear, and the used strips may be thrown 40 away.

45 From the above it will be seen that there is herein provided a device which embodies the features of this invention and achieves the objects thereof including many practical and useful advantages.

50 As many possible embodiments may be made of the above invention and as many changes might be made in the embodiment above set forth, it is to be understood that all matter hereinbefore set forth or shown in the accompanying drawing, is to be inter-

preted as illustrative and not in a limiting sense.

I claim as my invention:

1. A device for facilitating the slipping 55 of a necktie in a turned down collar, comprising a single integral strip of thin pliable paper of a width at least twice that of the necktie, folded along a longitudinal line and adapted to receive the necktie between the 60 folds thereof, said folded strip of paper having its inner walls glazed so that the necktie will slip readily therethrough and being adapted to be inserted, with the necktie therein and with the folded edge thereof 65 directed upwardly, between the inner and outer walls of the collar.

2. A device for facilitating the slipping 70 of a necktie in a turned down collar, comprising a single elongated strip of thin pliable paper interposed between a portion 75 of the necktie and a wall of the collar to hold said portion of the necktie out of engagement with the wall of the collar, the surface of said strip of paper engaging said necktie being glazed so that the necktie will slip readily along the same, said strip of paper being free from connection with the collar and having a portion folded over the top edge of the necktie to hold the strip 80 from slipping down relative to the necktie and out of the collar.

3. A device for facilitating the slipping 85 of a necktie in a turned down collar, comprising a single elongated strip of thin pliable paper interposed between a portion 90 of the necktie and a wall of the collar to hold said portion of the necktie out of engagement with the wall of the collar, the surface of said strip of paper engaging the walls 95 of the collar being unglazed and rough and adapted to frictionally engage the collar walls, said strip of paper being free from connection with the collar and having a portion folded over the top edge of the necktie to hold the strip from slipping down relative to the necktie and from within the collar.

In testimony whereof, I have signed my name to this specification this 3rd day of July, 1925.

THOMAS A. HART.
